UNITED STATES PATENT OFFICE

ALFRED J. BERG, OF ROCKINGHAM, NEW HAMPSHIRE

COUNTERBORING TOOL

Application filed September 10, 1928. Serial No. 305,013.

My invention relates to back counterboring and has for its object to provide a simple and effective means for holding the cutter for use in back counterboring onto the extension rod by which it is operated.

For the purpose of providing a suitable counterbore or countersink on the inside of armorplate for naval vessels to receive the head of a rivet it is often necessary, particularly in repairing armorplate in position, to introduce the extension rod of the tool from the outside and to fit onto the end of the extension, from the inside, the cutting tool required and to secure it on the extension so that by rotating this tool by a bit brace or other rotating means, the cutting tool may be rotated to cut away the metal on the inside end of a rivet hole already bored, as on account of restricted space within the armorplate it is difficult or impossible to rotate the counterboring or countersinking tool from the inside. In the counterboring or countersinking tools heretofore used for such work the cutter after being slipped onto the inner end of the extension rod has been held in place by a pin thrust through the cutter and into or through the extension rod. Under the conditions under which such tools are required to be used it is difficult to put the securing pin in place or to remove it and the pin is liable to be dropped causing delay to search for it or to obtain a new pin.

My present invention has for its object to provide a retaining means for the cutters of back counterboring or countersinking tools which will be always in place, will be readily turned to position to permit the cutter to be placed in position on the extension rod and to be then readily turned to position to retain the tool in position.

With the object above shown indicated and other objects hereinafter explained in view my invention consists in the construction and combination of elements hereinafter described and explained.

Referring to the drawings:

Figure 1 is a side view of a back counterboring or countersinking tool equipped with the retaining device embodying my invention.

Figure 2 is a side view of the end of the extension rod of the tool showing the rotary device in position to permit the cutting tool to be slipped onto it.

Figure 3 is a view similar to Figure 2 but showing the retainer turned to retaining position.

Figure 4 is a detail view of the retainer and

Figure 5 is an end view of the tool shown in Figure 1 showing the retainer in retaining position.

In the drawings 1 indicates the shank of my back counterbore adapted to be gripped in a bit brace or other means for rotating the tool. From this shank extends stem 2 which may be of any desired length. At its free end this stem is cut away to form the tool carrying portion 3 rectangular, or other than circular, in cross section adapted to receive the countersink or counterbore cutter 4. The end of the tool carrying portion is centrally bored at 5 and the bore is screw-threaded to receive the screw threaded portion 6 of a retainer for holding the cutter 4. This retainer comprises the screw threaded portion 6 and the head 7, the head having the same shape in cross section as the tool carrying portion 3. The threads on the portion 6 and in the bore 5 are so cut that when the retainer is screwed to bring it against the end of the tool carrying portion 3 it will be in the position indicated in Figures 1, 3 and 5, that is, its sides will be out of line with the sides of the tool carrying portion 3, after the cutter has been slipped over the retainer into operating position on the squared or otherwise non-circular portion 3, the retainer may, of course, be rotated in either direction to move its sides out of line with the sides of portion 3 so as to retain the cutter on the stem but the threads of the portion 6 of the retainer and the threads of the bore 5 are preferably so cut as to permit a slight rotation to bring it to retaining position.

As the retaining device need not be removed from the end of the stem to move from position to let the cutter slip over it to retaining position or back to permit the cutter

to be slipped off it will not be readily dropped or lost.

While this retaining device is particularly adapted and intended for use with the back counterboring or countersinking tools, I do not desire to be limited to its use with such tools as it is obviously adapted for holding any detachable cutter onto its stem.

Having thus described my invention what I claim is:—

10 In a boring tool having one end of its stem adapted to be engaged by means for rotating the tool and having the other end of the stem made non-circular in cross section and having
15 a screwthreaded bore extending into its end, a cutter adapted to be fit onto such non-circular end of the stem and a retainer carried by the stem having its head conforming in cross section to the non-circular end of the
20 stem and having a screwthreaded portion engaging the screwthreaded bore in the end of the stem.

In testimony whereof, I hereunto affix my signature.

25 ALFRED J. BERG.
